UNITED STATES PATENT OFFICE.

WENDELL L. CARLSON, OF WASHINGTON, DISTRICT OF COLUMBIA, ASSIGNOR TO
RADIO CORPORATION OF AMERICA, OF NEW YORK, N. Y., A CORPORATION OF DELA-
WARE.

ELECTRICAL COMMUNICATION.

Application filed September 21, 1922. Serial No. 589,726.

This invention relates to electrical communication and more particularly to amplifiers used in the reception of electrical signals.

The object of this invention is to embody certain new combinations in the construction of a plurality of iron core inter-valve amplifier transformers in a unit of extreme compactness.

10 A further object is to provide a construction which will greatly reduce the manufacturing cost of a plurality of inter-valve amplifier transformers.

15 My invention is especially adapted for the use in radio frequency transformers and will be described as such herein, but it is to be understood that the invention is broad enough to cover audio frequency transformer constructions as well.

20 Heretofore it has been customary to construct individual transformers for each stage of a cascade thermionic vacuum tube amplifier. I propose to assemble the various transformer windings of a cascade amplifier all in one iron core shell in such a way that part of the iron magnetic path will be common to adjacent windings.

25 In other cases where the amplifier is to operate over an extremely wide range of frequencies, I intend to design the individual windings in the transformer units differently, though employing one shell, and to connect their leads to a suitable switch so as to connect alternately the proper transformer with the amplifier circuit to operate on the particular frequency range it is designed for. In addition to the circuit arrangements described below, still other circuit arrangements employing this trans-
former are shown in my application Serial No. 30,036 filed May 13, 1925.

30 Referring to the drawing, Fig. 1 is a radio receiving circuit employing one radio frequency stage of amplification and a detector tube with three radio frequency transformers each designed to operate over a different frequency range. Fig. 2 is a plan view of three radio frequency transformers disclosing the arrangement of the iron core and windings as employed in Fig. 1. Fig. 3 is a radio receiving circuit employing three radio frequency stages of amplification and a detector.

The antenna circuit 1 in Fig. 1 is coupled

to the secondary tuned circuit 2 which connects to the input of the amplifying tube 3. The plate lead of tube 3 connects to a switch arm 11 which makes contact with points 12, 13 and 14 alternately as the arm is rotated at the will of operator. In like manner switch arm 15 is rotated simultaneously with arm 11 to make contact with points 16, 17 and 18. The primary windings of transformers 4, 6 and 8 are connected, at one end respectively to the contact points 12, 13 and 14 and the other ends known as the low potential terminals are connected to a common terminal and to the plate battery 19. The secondary windings of transformers 4, 6 and 8 are connected at their high potential ends to contact points 16, 17 and 18 and their low potential ends are connected commonly to the filament of detector tube 9. The grid of tube 9 connects through stopping condenser and grid leak unit 20 to the switch arm 15. Telephone receiver 10 is connected in the output circuit of tube 9.

35 In Fig. 2 the radio frequency transformers 4, 6 and 8 in Fig. 1 or Fig. 3 are shown as they are constructed in the transformer unit. 80 Each individual transformer has its own primary and secondary winding wound on a small laminated iron core plug 21. The laminated iron shell 22, having legs 24, completes the magnetic path around the coils thus forming what is generally known as shell type transformers. A certain degree of air gap 23 is usually allowed between core plug 21 and shell 22 so as to reduce the iron losses and regulate the permeability of the 85 magnetic path. In Fig. 3 the tuned antenna circuit is designated by numeral 1 which is coupled to a secondary tuned circuit 2 which in turn connects to the input of the amplifying vacuum tube 3. The output of tube 3 is coupled through the radio frequency transformer 4 to the input of amplifying tube 5. The output of tube 5 is in like manner coupled to the input of the third amplifying tube 7 through the transformer 100 6. Transformer 8 couples the output of tube 7 to the input of a detector tube 9 which has a telephone receiver 10 connected in its output circuit. The transformers 4, 6 and 8 have a common path for their magnetic flux in the laminated iron shell 22.

40 The operation of the circuit in Fig. 3 is so well known in the art that it need not be

dwell on extensively here, it being sufficient to say that the radio frequency carrier wave of the incoming signal is amplified through the vacuum tubes 3, 5 and 7 and that the 5 modulating component of the carrier frequency actuates the telephone receiver 10 due to the rectifying action of the detector tube 9. It has heretofore been thought that magnetic coupling between adjacent individual 10 transformers in the construction herein disclosed would create local oscillations in the accompanying tube circuits. In practical tests it has been found that the stray magnetic coupling obtained with such a transformer 15 construction on short wave lengths is practically negligible in so far as creating local tube oscillations is concerned. If on low radio frequencies or audio frequencies it is found that due to the greater penetration 20 of the magnetic field in the iron that coupling between the adjacent individual transformers creates troublesome effects, then by properly connecting the adjacent windings of the transformers, i. e., all windings in 25 same direction, the oscillating tendency of the circuit can be eliminated.

The operation of the circuit shown in Fig. 1 is similar to the operation of the circuit shown in Fig. 3 except that only one amplifying tube 3 is employed in conjunction with the individual transformers 4, 6 and 8 and the detector tube 9. The successive individual transformers 4, 6 and 8 are designed to cover different wave length ranges, i. e., 30 they differ in construction in the number of turns and air gaps 23 between shell 22 and plugs 21 and by switching to the proper transformer good amplification can be had over the range which the transformer is 35 designed to cover. While one radio stage is shown in this circuit it is obvious that any practical number of stages with a corresponding number of transformer units may 40 be employed.

45 Having described my invention, I claim:

1. A transformer element for ether wave signalling systems comprising a single magnetic shell having a plurality of legs, a plurality of magnetic core plugs mounted between pairs of legs of said shell providing slight air gaps between the plugs and the legs, and transformer primary and secondary windings on each core plug.

2. A transformer element for wave signalling systems comprising a single magnetic core shell having a plurality of legs, and a plurality of transformer primary and secondary windings mounted between pairs of said legs on core plugs providing air gaps between the legs and plugs, each transformer being wound and mounted to cover a different band of frequencies.

3. A transformer element for wave signalling systems comprising a single magnetic core shell having a plurality of legs,

and a plurality of transformer primary and secondary windings mounted between pairs of said legs on core plugs providing air gaps between legs and plugs, groups of said transformers being wound and mounted to 70 cover different bands of frequencies.

4. A transformer for wave signalling systems comprising a plurality of primary windings and a plurality of secondary windings mounted on a common magnetic frame 75 each set of windings adapted to pass radio frequency currents having a magnetic circuit including an air gap proportioned to increase the efficiency at radio frequencies.

5. A transformer for wave signalling systems comprising a plurality of pairs of primary and secondary windings and separate cores for each pair of said windings, magnetic paths for said pairs of windings having magnetic portions in common for two 85 pairs of windings, each set of windings adapted to pass radio frequency currents having a magnetic circuit including an air gap proportioned to increase the efficiency at 90 radio frequencies.

6. A high frequency transformer comprising a plurality of pairs of coacting windings, a magnetic core for each pair of coils and a magnetic structure joining said cores comprising a portion of a magnetic path in common for at least two of said pairs of coils, each pair of windings having a magnetic circuit including an air gap proportioned to increase the efficiency at radio frequencies. 95

7. A transformer comprising a plurality of pairs of coacting windings of different frequency characteristics mounted on a structure of magnetic material comprising a common portion for the magnetic paths of at least two of said pairs of windings, each pair of windings having a magnetic circuit including an air gap proportioned to increase the efficiency at radio frequencies. 105

8. A transformer comprising a plurality of pairs of coacting windings of different frequency characteristics mounted on a common core element of magnetic material, each pair of windings having a magnetic circuit including an air gap proportioned to 110 increase the efficiency at radio frequencies. 115

9. In ether wave signalling systems a plurality of radio frequency transformers, each of said transformers having a magnetic core and primary and secondary windings 120 adapted to pass radio frequency currents and a magnetic material providing a common path of magnetic flux connecting the cores of said radio frequency transformers.

10. In ether wave signalling systems a plurality of radio frequency transformers, each of said transformers having a magnetic core and primary and secondary windings 125 adapted to pass radio frequency currents and a closed magnetic circuit including at least 130

three legs one of said legs constituting a common magnetic path for said transformers.

11. The structure of claim 10 in which the 5 transformer cores are mounted between the legs and at substantially right angles thereto.

12. The structure of claim 10 in which a slight air gap is provided between each core 10 and leg.

13. A transformer core for ether wave signalling systems comprising a single shell of magnetic material having a plurality of legs and a plurality of cores of magnetic material mounted between said legs, the axes ¹⁵ of said cores being in substantial alignment whereby substantially balanced magnetic circuits are provided.

WENDELL L. CARLSON.
